UNITED STATES PATENT OFFICE.

WILLIAM C. CUTLER, OF NORTH GLENDALE, CALIFORNIA.

UNDERREAMER.

1,239,087.

Specification of Letters Patent.

Patented Sept. 4, 1917.

Application filed March 6, 1917. Serial No. 152,855.

To all whom it may concern:

Be it known that I, WILLIAM C. CUTLER, a citizen of the United States, residing at North Glendale, in the county of Los Angeles and State of California, have invented 5 a new and useful Underreamer, of which the following is a specification.

This invention relates to devices for underreaming a well below the inserted well-casing, and an object of the invention is to 10 simplify such device.

Another object is to save material in the cutters so as to leave little waste after the bit part of the cutters has been used up.

15 Another object is to so construct the cutters that the reaming and working of the cutters occurs under the most favorable condition for the cutters.

Another object is to shorten the working 20 levers of the cutters in relation to the body of the reamer.

Another object is to shorten the bit part 25 of the cutters below the body of the reamer, reducing the metal below the reamer body, reducing the price of extra cutters, shortening the lever between the cutting edge of the bit-part and the reamer body making it possible to provide a proportionately long 30 counter-lever toward the center of the reamer without having to use unnecessarily much metal in this part of the cutters, this again reducing the cost of extra cutters.

Another object is to bring the cutting 35 edge of the cutters close to the reamer body while providing for a proportionately large expansion causing the pounding of the cutters to be taken up by a strong solid end of the reamer body.

Another object is to eliminate all connecting rods, mandrels, spring-operated rods, center blocks, and other operating parts used in other under-reamers, the breaking of one of which usually making the whole device ineffective, thereby making this 45 device especially safe, besides being especially inexpensive and simple, which in turn makes this device durable.

Other objects and advantages will appear in the following description, claims and 50 accompanying drawing, in which—

Figure 1 is an elevation mainly in vertical mid-section of an under-reamer embodying my invention.

Fig. 2 is a section on line 2—2 of Fig. 1.

Fig. 3 is a section on line 3—3 of Fig. 1.

Fig. 4 is a similar view as Fig. 1, the cutters being slightly modified, the counter levers of the cutters in this figure being divided crosswise instead of in right angles to the cutting edges as shown in Fig. 1. 60

The lower end of the reamer body 1 is provided with a bore 2 concentric to the device. A circular cavity 3 is bored out at a suitable distance from the lower end of the bore 2 forming an annular shoulder 4 65 at the lower termination of the cavity or recess 3. The cutters 5 and 6 are provided with counter-levers 7 fitting in the bore of the reamer body below the cavity or recess 3. A projection 8 is formed on the upper 70 end of the counter-lever of each cutter normally engaging with the annular shoulder 4 in the body. The lower end of the body terminates in a full ring shaped surface which is used as the pounding surface upon 75 the cutters. The shoulder 9, formed on the cutters, rests smoothly against the full ring pounding surface of the body, while the cutting edges 10 of the cutters project beyond the body outwardly from the center 80 of the device in a practically parallel line with the periphery of the circular body. The projection 8 on the counter-lever of the cutters is cut off on one side forming the abutment 11 allowing the cutters to collapse to the position indicated at 12 bringing the abutment 11 toward the shoulder 4 in the recess 3 of the body 1. The cutters are thus mounted in the bore of the body 85 in pairs oscillating within the bore with the projections 8 resting on the shoulders 4 in the body. A spring 13 is inserted into the bore 2 above the counter-levers 7, on top of the projections 8 for holding the cutters in operative position. The counter-levers are 90 made so much smaller or narrower as to allow the projections 8 on the counter-levers to pass through the smaller lower bore 14, being the lower end of the bore 2 below the recess 3, a space 15 is thereby caused to remain as soon as the cutters are placed with the projections 8 on the shoulder 4, as 95 shown in Fig. 2.

To keep this space as narrow as possible and to keep the counter-levers as strong as 100 possible, the counter-levers are both together made slightly narrower than the diameter of the lower bore 14 plus one width of the shoulder 4, this making it necessary to insert one cutter first and placing same in 110

position with the projection 8 on the shoulder 4 and then insert the second cutter, as the space formed in the bore beside the first inserted cutter is then slightly larger than 5 the thickness of the projection on the counter-lever of the second cutter. After having inserted both cutters and placed them in position with the projections 8 on the shoulder 4, there is just a space 15 left of slightly. 10 more than one width of the shoulder 4, as will easily be understood.

To keep the cutters in this position, a distance plate or bar 16 is then inserted from below between the two cutters, and as 15 this bar is not subjected to any stress or pressure, a very small screw or pin 17 is sufficient to hold the bar in place.

To give a good seat for the spring 13, a ring 18 is inserted before the spring resting 20 against the taper termination of the bore 2, saving at the same time the work of having to be careful in drilling the bore and, by drilling, providing a square seat for the spring. Another ring or washer 19 is inserted below the spring on top of the cutters to provide a smooth surface for the oscillating counter-levers of the cutters.

To assure a central location for the two counter-levers of the cutters within the bore 30 14, projections or bosses 20 are provided on the lower end of the distance bar 16, for which suitable grooves 21 are provided in the counter-levers of the cutters, see Fig. 1. But it will easily be understood that the distance bar can be made so much thicker and the groove in the counter-levers can be of 35 the width of the whole bar, as indicated at 22, the chief point is to keep the two cutters apart by some means which will keep the projections of the counter-levers of the cutters on the shoulder in the body. The tops 40 27 of the counter-levers are sloping in normal position, causing the spring 13 to press upon the highermost points of these sloping tops only. The abutment 28, formed 45 on the lower side of the projection 8 is nearly parallel to the top, thereby bringing only the middle of the projection in touch with the shoulder 4, while the sloping abutment 28 allows the spring to cause a tilting 50 movement on the counter-lever, thereby holding the shoulder 9 of the cutter normally pressed against the ring termination of the body. This tilting movement of the 55 counter-levers and therewith the cutters, allows also a wear off of the ring termination of the body and of the shoulders of the cutters as the spring will naturally press the sloping levers and thereby adjust worn off 60 cutters to keep pressed toward the body preventing a clicking between the cutters and the body, the usual cause of rapid wear off.

A slightly modified construction of my 65 device is illustrated in Fig. 4. Instead of

dividing the counter-levers of the cutters in right angles to the cutting edges of the cutters as illustrated and described in the first three figures, the counter-levers of the cutters in this modified construction are divided 70 cross-wise to the cutters or in nearly a parallel line between the two cutting edges. This modified construction has the advantage over the first described cutters, that a pair of cutters can be turned out from a 75 piece of flat steel of the width equal to the diameter of the cutting edge and of the thickness equal to the width of the cutters, and, after having turned off the cutters to the desired dimensions, the finished piece is 80 simply cut in two on the lines 23, giving the two cutters for one reamer, as will easily be understood. The distance bar for this modified construction is a round bar 24 with the ring 25, which fits slidingly in the 85 bore 2, the ring being formed on the bar 24 or rigidly secured to the bar. For the bar 24 is a suitable recess bored into the end of the counter-levers while being turned, as will easily be understood. In pressing the cutters into the collapsed positions indicated at 26, the bar 24 is moved upwardly, the only difference of operation, the bar pressing on the centermost point of the counter-levers within the recess, as will also easily be understood. 90

The bar 24 rests in the recess on the counter-levers of the cutters without being held in place by a pin or key for interconnection with the body. The ring 25 simply 100 slides within the bore 2 of the body centralizing the bar and thereby holding the cutters in place.

The foregoing will be sufficient to enable those skilled in the art to make and use the invention which is understood to be only limited to a structure that is within the spirit and scope of the following claims. 105

I claim:—

1. In an underreamer a body comprising 110 a full circular bar having from the lower end upwardly a cylindrical main bore, the main bore being enlarged at the lower end for a suitable distance forming a cylindrical bearing surface, the main bore being furthermore enlarged above the cylindrical bearing surface into a cylindrical cavity forming an annular shoulder between the cylindrical bearing surface and the cylindrical cavity, cutters engaging with the body, and operating means disposed between the body and the cutters within the body. 115

2. In an underreamer a body being of 120 a full circular shape on the outside and having a concentric bore from the lower end upwardly, the bore being enlarged at the lower end for a suitable distance forming a cylindrical bearing surface, the bore being furthermore enlarged above the cylin- 125

drical bearing surface forming an annular shoulder above and adjacent to the cylindrical bearing surface in a plane at right angles to the axial line of the underreamer, 5 cutters engaging with the body, and operating means disposed between the body and the cutters within the body.

3. An under-reamer comprising a body having a concentric bore, the bore being enlarged at a suitable distance from the lower end, forming an annular shoulder within the bore, cutters having counter-levers fitting in the bore terminating in projections adapted for engaging with the annular shoulder in the body, and a spring inserted 15 into the bore seating on the counter-levers of the cutters.

4. An under-reamer comprising a body of substantially full circular outside having 20 a recessed center bore, cutters having enlarged ends toward the center engaging with the body adapted for oscillating movement within the recessed bore, and operating means placed above the cutters within the 25 body.

5. An under-reamer comprising a body of substantially circular cross section all over the part of the body inclosing the operating parts of the reamer having a central bore, the bore in the body being enlarged at a suitable distance from the lower end of the body upwardly, cutters having counter-levers projecting centrally and into the bore, the counter-levers terminating in enlarged ends adapted to engage with the body within the enlarged bore for oscillating movement, the cutters having also cutting edges extending outwardly from the center of the body in practically parallel lines with the periphery of the body, and operating means inserted above the counter-levers of the cutters within the body.

6. An under-reamer comprising a body of substantially circular cross section all over the part of the body inclosing the operating parts of the reamer having a recessed center bore, cutters having counter-levers projecting toward the center and into the bore of the body for oscillating movement within the recessed bore, a distance member mounted between the counter-levers of the cutters for holding the cutters within the enlarged bore yieldingly and swingably and operating means disposed between the body 55 and the cutters within the body.

7. An under-reamer comprising a body of substantially circular cross section all over the part of the body inclosing the operating parts of the reamer having a recessed bore, cutters having means to engage with the body within the recessed bore for oscillating movement, means for holding the cutters in position within the recessed bore, and means for holding the cutters in operative position yieldingly and swingably.

8. In an underreamer a body of substantially circular outside all over that part of the body which incloses the operating parts of the reamer having a central bore from the lower end upwardly, the bore being enlarged at a suitable distance from the lower end to a suitable distance upwardly forming a circular cavity or recessed bore above and below the remaining smaller cylindrical central bore, cutters engaging with the body, and operating means disposed between the cutters and the body within the body.

9. An under-reamer comprising a body having a concentric bore from the lower end upwardly, the bore being enlarged from a suitable distance above the lower end to a suitable distance upwardly forming an annular shoulder at the lower end of the cavity above the lower remaining center bore, cutters having counter-levers projecting centrally and into the bore in the body, the counter-levers terminating in enlarged ends adapted to engage with the annular shoulder in the cavity, the enlarged ends of the counter-levers on the cutters forming sloping tops in normal position for allowing tilting movement by means pressing on the highermost points of the sloping tops, the lower terminations of the enlarged ends on the counter-levers of the cutters forming also sloping surfaces nearly parallel to the tops for allowing a tilting movement of these sloping surfaces on the annular shoulder in the cavity in the body, and operating means inserted into the body above the sloping tops of the counter-levers on the cutters for automatically holding the cutters in operative position pressed against the lower end of the body.

10. An underreamer comprising a body having a concentric bore, the bore being enlarged at a suitable distance from the lower end forming an annular shoulder within the bore, cutters having means yieldably and swingably holding the cutters in the concentric bore of the body on the annular shoulder, and operating means inserted above the cutters within the body.

11. An underreamer comprising a body having a recessed concentric bore forming an annular shoulder near the lower end of the body within the bore, cutters having means swingably and yieldingly securing the cutters to the body when in operative position, and operating means loosely inserted in the body above the cutters.

12. An underreamer comprising a body having a recessed concentric bore forming an annular shoulder near the lower end of the body within the bore, cutters having means swingably and yieldingly securing the cutters in the recessed bore of the body, and operating means holding the cutters within the recessed bore of the body yieldingly and swingably.

13. An underreamer comprising a body having a recessed concentric bore forming an annular shoulder near the lower end of the body within the bore, cutters having means engaging yieldingly and swingably with the annular shoulder in the bore of the body when in operative position, and operating means securing the cutters within the recessed bore so that the said cutters may yield and swing below the body when so engaged within the recessed bore.
14. An underreamer comprising a body having a recessed concentric bore forming an annular shoulder near the lower end of the body within the bore, cutters having means engaging yieldingly and swingably with the annular shoulder in the bore of the body when in operative position, a distance member inserted between the cutters securing the cutters to the body within the recessed bore so that the cutting edges of the cutters may swing automatically into operative position and also into collapsed position while the distance member remains stationary, and operating means disposed above the cutters within the body.
15. An underreamer comprising a body having a recessed concentric bore forming an annular shoulder near the lower end of the body within the bore, cutters having means engaging swingably with the annular shoulder in the body, a distance member inserted between the cutters allowing the cutters to collapse when pressure is applied to the cutters in a downwardly direction on the cutting edges and also allowing the cutters to move automatically to the operative position when no pressure is applied to the cutting edges of the cutters in a downwardly direction, and a spring disposed between the body and the cutters surrounding the distance member within the body.
16. An underreamer comprising a body having a recessed concentric bore forming an annular shoulder near the lower end of the body within the bore, cutters having means engaging swingably with the annular shoulder in the body, a distance member secured to the body disposed between the cutters allowing the cutters to freely swing into operative position and into collapsed position, and means disposed in the body yieldingly holding the cutters in operative position.
17. An underreamer comprising a body having a recessed concentric bore forming an annular shoulder in the lower end of the bore, cutters having means engaging swingably with the annular shoulder in the body, a distance member removably secured to the body within the bore, the distance member securing the cutters swingably to the body without being connected to the cutters allowing the cutters to freely swing into operative position and into collapsed position, and means disposed in the bore of the body yieldingly holding the cutters in operative position.
18. In an underreamer, a cutter having a nearly semi-circular shank with the flat face at substantially a right angle to the cutting edge of the cutter, a shoulder extending laterally from the shank nearly parallel to the base line of the cutting edge, an abutment extending also laterally from the shank above the shoulder in sloping relation to the shoulder from about the middle of the nearly semi-circular shank extending slightly inclining upwardly in the opposite direction from the cutting edge forming the engaging member of the cutter, and a top surface on the shank in nearly parallel line with the abutment.
19. In an underreamer, a cutter having a counter lever with a flat face parallel to the center line through the cutter at substantially right angle to the cutting edge as seen in plan view, a shoulder extending laterally from the counter lever in practically parallel line with the base line of the cutting edge as seen in side elevation, an abutment extending also laterally from the counter lever above the shoulder in inclined relation to the shoulder from the middle of the counter lever slightly rising toward the side of the counter lever in the opposite direction of the cutting edge forming the engaging member of the cutter, a top abutment on the counter lever in nearly parallel lines with the engaging abutment forming the operating surface, and a collapsing abutment extending from the engaging abutment upwardly toward the top abutment on the same side of the counter lever with the cutting edge.
20. In an underreamer, a cutter having a counter lever with a flat face at substantially right angle to the cutting edge of the cutter, an engaging abutment opposite to the flat face extending laterally from the counter lever forming a circumferentially channeled neck, and a shoulder extending laterally from the shank below the abutment and above the cutting edge.
21. An underreamer comprising a body having a recessed concentric bore forming an annular shoulder in the lower end of the bore, a pair of cutters projecting with the cutting edges outwardly beyond and in nearly parallel lines with the periphery of the body having counter levers swingably fitting in the bore of the body engaging with the annular shoulder, the line of division between the counter levers of the two cutters being in right angles to the cutting edges, and operating means inserted in the bore holding the cutters in operative position.
22. An underreamer comprising a body having a recessed concentric bore forming an annular shoulder in the lower end of the

- bore, a pair of cutters projecting with the cutting edges outwardly beyond and in nearly parallel lines with the periphery of the body having counter levers swingably fitting in the bore of the body engaging with the annular shoulder, and a distance member slidingly inserted in the bore extending between the counter levers of the cutters so that the cutters may collapse and swing back into operative position upon corresponding pressure against the cutting edges
- 5 of the cutters, and a spring disposed in the body for automatically holding the cutters in operative position in combination with the distance member. 15
